(57) CLAIM

The ornamental design for an article of animal clothing, as shown and described.

DESCRIPTION

FIG. 1 is a left side elevational view of an article of animal clothing showing my new design;

FIG. 2 is a right side elevational view thereof;

FIG. 3 is a front elevational view thereof;

FIG. 4 is a rear elevational view thereof;

FIG. 5 is a top plan view thereof; and,

FIG. 6 is a bottom plan view thereof.

The broken line depiction of a dog in FIGS. 1 and 2 has been shown for the purpose of illustrating environment and forms no part of the claimed design.

1 Claim, 4 Drawing Sheets
